[57] CLAIM

The ornamental design for a support leg for portable toilet seats and the like, substantially as shown and described.

DESCRIPTION

FIG. 1 is a bottom perspective view of a support leg for portable toilet seats and the like showing my new design, with the leg in a closed position;

FIG. 2 is a top perspective view of FIG. 1;

FIG. 3 is another bottom perspective view thereof showing the leg in an open position;

FIG. 4 is another bottom perspective view of FIG. 1; and

FIG. 5 is another bottom perspective view of FIG. 3.

The broken line representation of a toilet seat and support legs in FIGS. 4 and 5 are for purposes of illustration only and form no part of the claimed design.
